Albert G. Prestol Day for Stoves
Patented Jan 28, 1846.

Des. 45

Albert G. Bristol, Rochester, New York

Letters Patent (Design No. 45) dated 33rd January 1846
ante dated Sept 22nd 1845

The Schedule referred to in these Letters Patent and
making part of the same

To all whom it may concern: Be it known that I, Albert G. Bristol of the city of Rochester in the County of Monroe and State of New York, have invented a new and original design carved in alto relief and I do declare that the following is a full and exact description. The design consists:

1st In a vase with flowers leaves and buds springing therefrom which are carved in alto relief, and marked

J

Des. 45

A in the accompanying drawings.

2^d In curtains with cords & tassels fastening, said curtains aside carved in like manner & marked B.B. in the drawing.

3^d In a bunch of leaves and stem carved in like manner and marke C in the drawing.

These ornaments I make of Cast Iron, to be parts of an ornamental or parlour stove.

What I claim as my invention and desire to secure by Letters Patent is the combination of the ornament marked C in the accompanying drawings, with the ornament marked B.B; the 1st consisting of a bunch of leaves & stem & the 2^d of curtains, cords & tassels; these two being either combined or not with the ornament marked A in the drawing consisting of a vase with flowers leaves & buds all being carved in alto relief & made in manner & form as shown in the accompanying drawing, from cast Iron, thus composing a new design for a stove.
